WOOD HEEL TURNING MACHINE

Filed Aug. 17, 1927

Fig. 2.

UNITED STATES PATENT OFFICE.

NORTON W. KINNEY, OF HAVERHILL, MASSACHUSETTS, ASSIGNOR TO SLIPPER CITY WOOD HEEL COMPANY, OF HAVERHILL, MASSACHUSETTS, A CORPORATION OF MASSACHUSETTS.

WOOD-HEEL-TURNING MACHINE.

Application filed August 17, 1927. Serial No. 213,600.

This invention relates to heel turning machines and is illustrated as embodied in a wood heel turning machine of the type disclosed in United States Letters Patent No. 5 1,580,184, issued April 13, 1926, on the application of John H. Vinton.

Machines of the type mentioned are provided with a jack for holding a wood heel blank and swinging it past a rotary cutter. 10 The jack comprises a base plate on which the heel-seat portion of the blank rests, and a clamping member which may be swung into engagement with the toplift portion of the blank. The clamping member is operated by 15 a clamping lever which throws it toward the base plate, the clamping lever having an adjustable screw in its end by which it contacts with the clamping member. The clamping lever is operated by a cam lever which throws 20 it always to the same position, and adjustment of the screw is necessary to enable the clamping lever to bring the clamping member into proper contact with heel blanks of varying sizes. When using good uniform 25 lumber, a single adjustment of the screw is sufficient for a considerable run of blanks.

It is the object of the present invention to provide an improved jack of the type referred to by the use of which the handling of 30 blanks made of the cheaper grades of lumber and lacking uniformity in thickness may be facilitated. To this end I have provided what is in effect a resilient clamping lever, which, in the present embodiment of the invention, is shown as a compound clamping 35 lever having two resiliently connected portions so that any lack of uniformity in the thicknesses of the work pieces is absorbed in the resilient connection, and the screw adjustment need be resorted to but seldom.

These and other features of the invention comprising certain combinations and arrangements of parts will be apparent from the following description of a preferred embodiment of the invention shown in the drawings, in which

Fig. 1 is a side elevation of the front part of the machine; and

Fig. 2 is a sectional detail of the resilient compound clamping lever.

In the drawings only so much of a wood heel turning machine is shown as is necessary

for the understanding of the present invention, and reference may be made to Letters Patent No. 1,580,184, above referred to, for further illustration and description of the construction and operation of parts not fully disclosed herein.

The frame 10 of the illustrated wood heel turning machine has a vertical cutter shaft 12 with a formed cutter head 14. The frame also carries a shaft 16, parallel to the cutter shaft, on which is mounted a swinging bracket or crane 18 carrying a pivoted shaft 20 in its outer end. This shaft is moved vertically by the engagement of an arm 22 on its lower end with a pivotally adjustable so-called lower track 24, and carries at its upper end the jack holder 26. Pivotally mounted in the jack holder at 28 is the jack frame 30, having a base plate 32 arranged to engage the heel-seat portion of a wood heel blank, a breast gage 34, and a toplift portion clamping member 36. The member 36 is mounted on a horizontally adjustable pivot 38 having the considerable range of adjustment necessary to enable its end to overlap and engage properly with the toplift end of any type of heel blank 39.

A clamping lever 40 is pivotally mounted 80 at 42 on the jack frame 30. This lever 40 has a screw 44 mounted in its end, over the clamping member 36. When the heel blank is clamped the member 40 is forced to the position shown in Fig. 1 by mechanism to be described, and gross variations in the thickness of the work are accommodated by adjustment of the screw up and down in the end of the lever 40, so that any thickness of blank can be clamped with the member 40 in substantially the same position. The member 36 is normally held up against the screw 44 by a spring 45. The upper surface of the member 36 is provided with a number of seats 48, each adapted to receive the screw 44, these seats 95 consisting of holes or drill spots, arranged along the length of the member 36, so that any longitudinal adjustment of the member 36 will bring one of these seats nearly under the screw 44. The screw 44 is threaded into a trunnion piece 50, which is horizontally pivoted in the end of the clamping member 40, thus permitting the screw to swing in the vertical plane of the member 36, and to find

the convenient seat 48 for any given condition. A jam nut 52 or any other convenient device can be used to preserve the adjustment of the screw in the trunnioned nut 50.

- 5 Minor variations in height of the work pieces are compensated for by the present invention by providing a resilient clamping lever consisting of the member 40 and a lever 56 terminally pivoted at 58 on the member 40.
- 10 A spring 54 is mounted in seats 55, one in the end of the member 40 and the other in the middle part of the lever 56. A cam roll 60 is mounted at the other end of the lever 56, engaging a cam 62 on a cam lever 64 pivoted 15 at 66 on the jack frame 30.

The screw 44 will be adjusted so that the operation of the lever to jack a blank will appreciably compress the spring 54. Small variations in the work thickness will vary the 20 compression correspondingly, but leave the blank 39 under substantial clamping pressure, and the operator is thus relieved of the duty of frequent adjustment during a run of heels.

- 25 In the drawings the jack is shown in blank-clamping position. To release the blank the operator will raise the handle 68 causing the cam 62 to run from under the roll 60. This will release the members 56, 40 completely so 30 that they can swing around the pivot 42 releasing the member 36, when the blank can be removed and a new one inserted. The members 36, 40, the pivots 38, 42, 50 and the depression 48 constitute a linkage which 35 changes its form as the member 36 is forced down on the heel blank 39. The pivot at 50 prevents any tendency of the end of the screw 44 to scrape over the top of the member 36 as this change in form takes place and avoids 40 any danger of breaking or damaging the screw or the member 36. The jack as a whole is tilted around the pivot 28 by the adjustable so-called upper track 70, as will be well understood by those familiar with the art.

- 45 The organization of the adjusting screw 44 and the adjustable clamping member 36 so that they co-operate smoothly in all their relative adjustments, as exemplified in the 50 pivotal mounting for the screw and its seats in the member 36, embodies an invention of Walter W. Bradbury described and claimed in his application Serial No. 195,117, filed May 28, 1927, and is not claimed herein.

Having thus described my invention, what 55 I claim as new and desire to secure by Letters Patent of the United States is:

1. In a machine for turning wood heels, a rotary cutter, a swinging jack arranged to hold and rotate a wood heel blank against the 60 cutter, said jack comprising a clamping member arranged to press against the heel blank, and means for operating the clamping member comprising a resilient lever and means for operating the resilient lever.
- 65 2. In a machine for turning wood heels, a

jack comprising a clamping member arranged to press against a heel blank, and means for operating the clamping member comprising a resilient lever and a cam lever for operating the resilient lever.

70

3. In a machine for turning wood heels a jack comprising a support for a heel blank, a compound lever arranged to force the heel blank against the support, said lever being resiliently held in a normal position, and means for operating said lever arranged to distort it resiliently while throwing it toward the blank.

75

4. In a machine for turning wood heels, a jack comprising a support for a heel blank, a clamping member arranged to hold the heel blank against the support, and means for operating the clamping member comprising a compound lever, a spring located between the arms of the compound lever, and an operating means for the compound lever, one arm of the compound lever being arranged to engage the clamping member, and the other arm being arranged to engage the operating means.

80

5. For use in a machine for turning wood heels, a jack comprising a member movable to engage one face of a heel blank, a clamping member movable to hold the blank against the said member, and means for operating the clamping member comprising a clamping lever pivoted on the jack frame, and arranged to engage the clamping member, a second lever pivoted on the clamping lever and having a resilient bearing against it, and a cam lever arranged to engage the second lever to operate the clamping lever.

85

6. In a machine for turning wood heels, a jack comprising a support for a heel blank, a clamping member arranged to clamp the blank against the support, and means for operating the clamping member comprising a clamping lever pivoted on the jack frame, a second lever pivoted on the clamping lever, a spring extending between the two said levers, and an operating lever arranged to engage the second lever.

90

7. In a machine for turning wood heels, a jack comprising a clamping member arranged to contact with a heel blank, and means for operating the clamping member comprising a clamping lever pivoted near its middle on the jack frame with one of its ends engaging the clamping member, a second lever pivoted adjacent the other end of the clamping lever, said two levers having oppositely located seats, a spring located in the seats, a bolt extending through the levers and the spring to hold the spring under tension, and an operating cam lever constructed and arranged to engage the second lever.

95

8. In a machine for making wood heels, a rotary cutter and a jack for holding and rotating a wood heel blank against the cutter, said jack comprising a support for the wood

100

heel blank, a resilient lever arranged to force the blank toward the support and means for operating the lever, the lever being arranged to be resiliently distorted by the force impressed on it by the operating means and the blank, whereby it can cooperate with blanks of varying thickness.

9. In a machine for making wood heels, a support for a heel blank, a resilient clamping lever arranged to force the heel blank toward the support, said lever having an adjustable part arranged between it and the blank to avoid undue extremes in the operative position of the clamping lever, and means for operating the resilient lever to bring it into operative position, the resiliency of the lever

compensating for minor inequalities in the thickness of the work.

10. In a machine for making wood heels, a support for a heel blank, a resilient clamping lever arranged to force the heel blank toward the support, said lever having an adjustable screw arranged between it and the blank to avoid undue extremes in the operative position of the clamping lever, and means for operating the resilient lever to bring it into operative position, the resiliency of the lever compensating for minor inequalities in the thickness of the work.

In testimony whereof I have signed my name to this specification.

NORTON W. KINNEY.
